DESIGN FOR A COMBINED OIL CAN OPENER AND DISPENSER

Moritz Gaertner, New York, N. Y.

Application July 19, 1933, Serial No. 48,760

Term of patent 3½ years

To all whom it may concern:

Be it known that I, Moritz Gaertner, a citizen of the United States and a resident of city, county, and State of New York, have invented a new, original, and ornamental Design for a Combined Oil Can Opener and Dispenser, of which the following is a specification, reference being had to the accompanying drawing, forming a part thereof.

Fig. 1 is a top plan view of a combined oil can opener and dispenser embodying my new design.

Fig. 2 is an elevational view of the combined oil can opener and dispenser embodying the design.

I claim:

The ornamental design for a combined oil can opener and dispenser, as shown.

MORITZ GAERTNER.
